UNITED STATES PATENT OFFICE.

SIDNEY E. PARKER, OF SOUTHAMPTON, ENGLAND, ASSIGNOR OF ONE-HALF TO HENRY J. OSMAN, OF SOUTHAMPTON, ENGLAND.

DESIGN FOR A CLAW-HOOK.

47,008.

Specification for Design.

Patented Feb. 23, 1915.

Application filed October 9, 1914. Serial No. 865,941. Term of patent 7 years.

To all whom it may concern:

Be it known that I, SIDNEY E. PARKER, a subject of the King of Great Britain, residing at Southampton, in England, have invented a new, original, and ornamental Design for Claw-Hooks, of which the following is a specification, reference being had to the accompanying drawing, forming a part thereof.

The figure is a perspective view of a claw hook, showing my new design.

I claim:

The ornamental design for a claw hook, as shown.

S. E. PARKER.
